UNITED STATES PATENT OFFICE.

JAMES E. DIAMOND, OF CLEVELAND, OHIO.

INTERNAL-COMBUSTION ENGINE.

1,311,213.

Specification of Letters Patent. Patented July 29, 1919.

Application filed June 14, 1917. Serial No. 174,698.

To all whom it may concern:

Be it known that I, JAMES E. DIAMOND, a citizen of the United States, residing at Cleveland, in the county of Cuyahoga and State of Ohio, have invented certain new and useful Improvements in Internal-Combustion Engines, of which the following is a specification, reference being had therein to the accompanying drawing.

10 This invention relates to an improved frame and cylinder construction for internal combustion engines.

One object of the invention is to provide an internal combustion engine having a 15 light weight in relation to its power capacity.

Another object of the invention is to provide an internal combustion engine having high thermodynamic and mechanical efficiency.

A further object of the invention, ancillary to the foregoing objects, is to provide an improved composite frame and cylinder construction in which the main frame parts 25 are formed of light weight metal or alloy while the walls of the cylinders proper are formed of different material having suitable wear-resisting qualities and are permanently secured to the main frame parts when the 30 latter are cast.

Other objects which I have sought to attain will be understood from the following description in which I set forth, in connection with the accompanying drawings, preferred embodiments of the invention.

In the drawings,

Figure 1 is a transverse vertical section through one of the cylinders of an engine embodying my improvements, the section 40 being taken on the line 1—1 of Fig. 2.

Fig. 2 is a bottom view of the cylinder head casting.

Fig. 3 is a plan view of the upper part of the main frame casting of the engine.

45 Fig. 4 is a fragmentary transverse vertical section through the frame and cylinder of an engine showing a modified form of construction.

In the drawings, 1 indicates as an entirety 50 the main frame casting of the engine which

is preferably formed of metal of low specific gravity, such as a suitable aluminum alloy. This casting comprises the upper part 1^a of a closed crank case and the walls of a water jacket 1^b, the crank case and jacket parts 55 of the casting being joined by a contracted section 1^c. In its upper part the casting 1 is formed with a series of horizontally disposed rings 1^d, 1^e, 1^f, 1^g, said rings being connected with the main walls of the casting 60 1 by bridge or tie parts 1^h, 1ⁱ. The rings 1^d, 1^e and 1^f, 1^g, respectively, are preferably united at 1^m and 1ⁿ.

The cylinders proper are in the form of sleeves 2, 2 of suitable wear-resisting material. In the construction shown in Fig. 1 the cylinder sleeves are preferably formed of iron or steel. At their upper ends the cylinder sleeves 2 are permanently rigidly attached each to one of the rings 1^d, 1^e, 1^f 75 and 1^g, while their lower parts extend through the contracted section 1^c of the frame casting and project into the chamber of the crank case. The cylinder sleeves fit tightly but movably in the contracted section 1^c of the casting 1, each sleeve being surrounded by a metallic packing ring 3 to insure a water tight joint. The sleeves are permanently united to the frame casting 80 when the latter is formed. As iron and steel have coefficients of thermal expansion differing widely from that of aluminum alloy employed for the main frame casting 1, I have devised a form of construction 75 which provides for differences of expansion 85 of the parts due to the heat of combustion within the cylinder, and I will now describe in detail the manner in which this construction is produced.

The cylinder sleeves are preferably machined inside and outside and at their upper ends are externally formed with projections adapted to interlock with the metal of the casting 1. Such projections can conveniently be formed by threading the upper 90 end of the cylinder as indicated at 2^a and then grooving it longitudinally as at 2^b. When the sleeves have been prepared in this manner, I next coat the threaded outer surface with a metal, such as copper, which is 95 100

adapted to fuse both with the iron or steel of the cylinder sleeve and with the aluminum alloy of the frame casting 1. The copper or other metal coating may be applied 5 by plating or in any well known way. I next coat the exterior surface of the lower part of each cylinder sleeve with graphite or the like where the sleeve is to extend through the contracted part 1^c of the frame casting. 10 The metal packing rings 3 are then slipped over the cylinder sleeves and the latter are suitably placed in the mold in which the main frame casting is to be poured. The frame casting is then poured and its molten 15 metal forming the rings 1^a, 1^b, 1^c and 1^d fuses with the upper ends of the cylinder sleeves 2 or, rather, with the copper or other coating on the sleeves 2, which coating in turn fuses with the metal of the sleeves 20 so that the latter at their upper end are practically integrally united with the metal of the main frame casting 1. At the lower ends of the cylinder sleeves where they pass through the contracted parts 1^c of the frame 25 casting, the coating of graphite prevents the aluminum alloy of the frame casting from fusing with the metal of the cylinder sleeves so that when the main frame casting is cooled it fits very snugly around the lower 30 parts of the cylinder sleeve but is not integrally united with said parts; on the contrary, it is free to move longitudinally of the cylinder sleeves under the great stress of thermal expansion when the parts expand 35 unequally.

On the upper part of the frame and cylinder structure is mounted a head casting 4 which is also preferably formed of metal of low specific gravity similar to that employed 40 for the main casting 1. The head casting is removably secured to the main casting by screw bolts 5, 5, a suitable gasket 6 being interposed between the two castings to insure a water and gas tight joint. The head 45 casting is formed with a series of combustion chambers 4^a, one for each cylinder of the engine. The head casting is also formed with inlet and exhaust passages 4^b and 4^c for each of the combustion chambers. The said 50 passages are controlled by puppet valves 7 and 8 which cooperate with seats 9 and 10. These seats are preferably formed of wear-resisting metal such as bronze or alloy steel and may be secured to the head casting in 55 any suitable manner as by casting them in when the head casting is formed. The valves may be actuated in any suitable manner as by the cam operated rocker arms 11, 12 and springs 13, 14.

60 The head casting is chambered out to form a water jacket space 4^d which surrounds the combustion chamber and the inlet and exhaust passages 4^b and 4^c. The water jacket space 4^d of the head casting, as will be seen 65 from an inspection of Figs. 2 and 3, is freely

open to the water jacket space surrounding the cylinders 2. At a suitable point in the jacket wall 1^b I form a water inlet opening 1^e and at one end of the head casting 4 I form water outlet openings 4^e. These inlet 70 and outlet openings may be connected in any suitable manner with a radiator or other cooling apparatus.

The head casting 4 is provided, in connection with each combustion chamber, with a 75 cylindrical conduit 4^f each of which opens into one of the combustion chambers and is adapted to receive a spark plug.

In each of the cylinder sleeves 2 is arranged a piston 15 preferably formed of an 80 aluminum alloy or other metal of light weight and high thermal conductivity in comparison with iron. Each piston is operatively connected by connecting rod 16 with the crank shaft 17, said shaft being suitably 85 mounted in bearings carried by the main frame casting 1. 18 is the bottom or pan member of the crank case. It is bolted in the usual manner to the upper part of the crank case and serves in connection therewith to 90 entirely inclose the crank shaft, connecting rods, etc.

It will be seen that I have produced a form of construction that materially reduces the weight of the engine, as compared with 95 prior forms of construction. In fact, by forming the upper part of the crank case and the water jacket walls in a single casting of light weight metal, making the head casting of a similar light weight metal and making the cylinders proper in the form of relatively thin sleeves, I not only reduce the weight of the engine to a minimum but attain high thermo-dynamic and mechanical efficiency, the gain in efficiency arising from 100 the fact that the cylinder wall can be made of selected materials especially suited to the purpose and also from the fact that said walls, formed of suitable material, can be made thin and of uniform thickness so that 110 their contraction and expansion will be uniform throughout. Under these conditions mechanical friction between the piston and cylinder wall is reduced to a minimum and the working temperature of the engine can 115 be controlled to secure a maximum of thermodynamic efficiency.

As previously explained, the cylinder sleeves 2 are practically integrally united with the metal of the cylinder casting 1, so 120 that there is no possibility of leakage. For that matter the joints between the cylinder sleeves and the frame casting 1 are covered by the gasket 6. At the lower end of the water jacket space, the joints between the 125 cylinder sleeves and the casting 1 permit of longitudinal expansion or contraction of the cylinder sleeves in relation to the frame casting but provide so snug a fit between the parts that leakage is obviated.

In Fig. 4 of the drawing I show a modified form of construction which contemplates the use of bronze or other alloy for the cylinder sleeves in lieu of iron or steel. Certain 5 bronzes have very excellent bearing and wear-resisting qualities and coefficients of thermal expansion approaching those of aluminum alloys such as are suitable for the main frame casting of the engine. Therefore, 10 by using such material for the cylinder sleeves, it is possible to integrally unite the latter with the main frame casting at both ends of the sleeves without having the structure subjected to unduly large stresses incident to differences of expansion and contraction. 15 In Fig. 4 I show a construction of this character comprising a main frame casting 31 which is for the most part similar to the casting 1 in the form of construction shown in Fig. 1. However, in this case the cylinder sleeves 32 are formed of bronze and have their upper ends threaded as at 32^a and grooved as at 32^b. They also have their lower parts, where they extend through the contracted part 31^c of the main frame casting, threaded as at 32^c and grooved as at 32^d. In producing this form of construction the bronze cylinder sleeves may be placed in the mold for the frame casting and when the latter is poured the molten aluminum alloy fuses with the bronze of the sleeve so that the sleeves have their upper ends integrally united to the rings 31^d and their lower parts similarly united to the contracted part 31^c of the casting 31.

The forms of construction which I have shown and described are for the purpose of illustration and explanation and it will be understood that many modifications and 40 variations can be made without departing from my invention.

What I claim is:

1. In an internal combustion engine, the combination with a cylinder sleeve of wear-resisting metal, of a frame casting of light weight metal shaped to form water jacket walls surrounding and spaced from the cylinder sleeve so that the jacket water comes in direct contact with said sleeve, the frame casting being permanently rigidly united to the upper end of said sleeve by being cast thereon.

2. In an internal combustion engine, the combination with a cylinder sleeve of wear-resisting metal, of a frame casting of light weight metal shaped to form the upper part of a crank case and water jacket walls surrounding and spaced from the cylinder sleeve so that the jacket water comes in direct contact with said sleeve, the frame casting being permanently rigidly united to the upper end of the cylinder sleeve by being cast thereon.

3. In an internal combustion engine, the

combination of a cylinder sleeve of wear-resisting metal, a frame casting of light weight metal shaped to form the upper part of a crank case and water jacket walls surrounding and spaced from the cylinder sleeve so that the jacket water comes in direct contact with said sleeve, the frame casting being permanently rigidly united to the upper end of the cylinder sleeve by being cast thereon, and a cylinder head casting of light weight metal separably secured to the upper end of the frame casting.

4. In an internal combustion engine, the combination with a cylinder sleeve of ferrous metal, of a frame casting of aluminum alloy shaped to form water jacket walls surrounding and spaced from the cylinder sleeve so that the jacket water comes in direct contact with said sleeve, the frame casting being permanently rigidly united to the upper end of said sleeve by being cast thereon.

5. In an internal combustion engine, the combination with a cylinder sleeve of ferrous metal, of a frame casting of aluminum alloy shaped to form the upper part of a crank case and water jacket walls surrounding and spaced from the cylinder sleeve so that the jacket water comes in direct contact with the said sleeve, said jacket walls being permanently rigidly united to the upper end of the cylinder sleeve by being cast thereon and in tight movable contact with the lower part of the cylinder sleeve in a zone between the water jacket and crank case.

6. In an internal combustion engine, the combination with a cylinder sleeve of wear-resisting metal, of a frame casting of light weight metal shaped to form water jacket walls surrounding and spaced from the cylinder sleeve so that the jacket water comes in direct contact with said sleeve, the frame casting being permanently rigidly united to the upper end of said sleeve by being cast thereon, and means for forming a water tight joint between the casting and the cylinder sleeve at the bottom of the water jacket.

7. In an internal combustion engine, the combination with a cylinder sleeve of wear-resisting metal, of a frame casting of light weight metal shaped to form water jacket walls surrounding and spaced from the cylinder sleeve so that the jacket water comes in direct contact with said sleeve and also shaped to form a horizontal annular wall disposed within the upper part of the jacket walls and permanently rigidly united to the upper end of the cylinder sleeve by being cast thereon.

8. In an internal combustion engine, the combination of a cylinder sleeve of wear-resisting metal, a frame casting of light weight metal shaped to form water jacket walls surrounding and spaced from the

cylinder sleeve so that the jacket water comes in direct contact with the said sleeve and comprising a horizontally disposed annular wall within the upper part of the jacket walls and bridge parts uniting the annular walls and the jacket walls and leaving upwardly opening passages for water, and a

cylinder head casting of light weight metal having a water jacket chamber connecting with the said water passages of the frame 10 casting.

In testimony whereof, I affix my signature.

JAMES E. DIAMOND.
